UNITED STATES PATENT OFFICE.

JAMES A. SCROGGIN, OF LITTLE ROCK, ARKANSAS.

MUSIC-LEAF HOLDER.

1,217,840.

Specification of Letters Patent. Patented Feb. 27, 1917.

Application filed February 28, 1916. Serial No. 80,862.

To all whom it may concern:

Be it known that I, JAMES A. SCROGGIN, a citizen of the United States, and a resident of Little Rock, in the county of Pulaski and State of Arkansas, have invented a certain new and useful Improvement in Music-Leaf Holders, of which the following is a specification.

One of the principal objects of the invention is to provide an improved music leaf holder, of booklike form, which may be used in holding sheets of music of various sizes, the device being of such nature that it may be mechanically operated for turning the sheets of music one at a time, without the necessity of the operator or musician removing his hand from the instrument he is playing.

Another object of the invention is to provide an improved method of constructing, mounting, and operating a music sheet holder.

A further object of the invention is to provide an improved music sheet holder having a novel means of releasing the frames which support the music sheets.

Still another object of the invention is to provide an improved device of the class described which will be extremely simple, durable, efficient in operation, and inexpensive to manufacture.

With these and other objects in view which will become apparent as the description proceeds, the invention resides in the construction, combination, and arrangement of parts hereinafter more fully described and claimed, and illustrated in the accompanying drawings in which like characters of reference indicate like parts throughout the several figures, of which—

Figure 1 represents a face view of the device.

Fig. 2 represents a detail section through the pneumatic plunger means, showing the cylinder and a portion of the rack.

Fig. 3 represents an enlarged detail sectional view on the line 3—3 of Fig. 1.

Fig. 4 represents a section along the line 4—4 of Fig. 1, looking in the direction indicated by the arrow.

Fig. 5 represents an enlarged detail section through the slide and guide, taken along the line 5—5 of Fig. 1.

Fig. 6 represents a sectional view through the slide, on the line 6—6 of Fig. 1.

Fig. 7 represents a sectional view along the line 7—7 of Fig. 1.

Fig. 8 represents a perspective view of the upper portion of one corner of the assembled frame.

Fig. 9 represents an enlarged detail view of a portion of one of the frames, showing the spring for swinging the same.

In carrying out my invention I provide a casing consisting of flat leaves 5 and 6 hingedly connected at their near ends to a transversely curved back 7 in such manner that the leaves may be swung one relatively to the other in order to open the casing outwardly in the form of a book in the manner indicated in dotted lines in Fig. 4. The leaf 5 is provided at its top and bottom edges with upwardly extending walls 8, and along its outer longitudinal edge with a hinged wall 9, which may be shifted from the vertical position assumed when the casing is in closed position, to the downwardly extending dotted line position indicated in Fig. 4, whereby to retain the leaf 5 in a plane substantially parallel with the plane in which the leaf 6 lies when the casing is in open position. This leaf 6 is provided along its outer longitudinal edge with a downwardly extending lip 10 which may engage over the upper edge of wall 9 when the casing is closed, as indicated in Fig. 4.

Suitably connected at its ends adjacent the inner ends of side walls 8, and slightly spaced above the leaf 5, is a rod 11, upon which the frames to be hereinafter described, may swing as a pivot. Rotatably mounted upon this rod are the L-shaped arms 12. To each of the latter is connected one end of a coiled spring 13, which surrounds the rod and whose opposite end is suitably connected to said rod. The outer portions of arms 12 extend in parallel relation with the rod, and are provided with squared recesses for the reception of the downturned square ends 14 of arms 15 provided each upon one of the rectangular frames 16. Set screws or other suitable means 17 as indicated clearly in Fig. 9 may be used if desired, to prevent accidental disengagement of the arms 15 and 12. The frames 16 are preferably rectangular in shape, and are preferably made of thin, light strong steel or aluminum or other metal. The frames are made as thin as possible consistent with their required

strength, so that a comparatively large number of them may be piled one upon another and yet take up a minimum amount of room.

5 Arranged longitudinally upon each of the frames 16 is a pair of bars 18. The latter are preferably formed of thin strips of steel overturned at their ends upon the end bars of the frame as at 19, in order to slidably 10 engage said end bars. These bars 18 may be moved toward and away from each other to accommodate sheets of music of various widths. At intervals bars 18 are punched or stamped whereby to form spring fingers 15 20 extending alternately on opposite sides of the bars, and projecting toward their inner edges, whereby sheets of music may be engaged beneath these spring fingers and on opposite sides of said bars. In this manner, 20 each of the frames 16 carries if necessary two sheets of music, one sheet disposed upon each side of the frame. The bars 18 may be taken off of or put upon the frame 16 by slipping them in the desired direction along 25 the upper and lower bars of said frame.

The frames 16 are provided on their outer edges and adjacent their upper corners with the retaining lugs 21 preferably formed integrally with said frames. These lugs are 30 adapted to be normally engaged by the releasing mechanism to be hereinafter described, whereby to maintain said frames upon the right hand side of the device. This releasing mechanism includes a guide 35 bar or rod 22 extending between the walls 8 of leaf 5 and in parallel relation with and slightly spaced from the frames 16. A sectional slide consisting of a rack bar 23 and lower sections 24 is provided. This rack bar 40 has a channel formed in its upper face into which the guide bar 22 fits, and belts or ties 25 bridge the channel above the guide 22 in order to slidably retain said rack bar in position. Depending flanges 26 having inwardly projecting lips 27 extend along the longitudinal edges of the rack bar 25. Between these flanges 26 are retained against the rack bar through the action of the lips 45 27, are disposed the lower sections 24 of the 50 releasing device.

The holding lugs 21 are arranged with respect to the releasing device in series of three. That is, the holding lugs of the topmost second and third lower frames lie in 55 a single plane, while the lugs of the fourth, fifth and sixth frames lie in a plane below the plane in which the first lugs lie, and spaced therefrom a distance substantially equal to the thickness of one of the lower 60 sections 24 of the releasing mechanism. The arrangement whereby the lugs may be arranged in tiers is shown in Fig. 8, from an inspection of which it will be seen that the lug on the second lower frame occurs a distance 65 from the upper edge of the frame

equal to the length of the first lug, and the lug on the third frame occurs a distance equal to the length of the first two lugs. Furthermore, it will be seen that the lugs on the second and third frames are of such 70 length that they may be bent up to lie in a plane coincident with the plane in which the first lug occurs. As shown in Fig. 6, the next tier of retaining lugs 21 occurs in a plane spaced from that in which the first tier 75 lies.

The releasing device is of a width greater than the width of the guide 22, and the outer ends of the retaining lugs engage beneath the adjacent edge of the releasing device, but 80 do not underlie the guide bar. As indicated in Fig. 6, the first three lugs or the first tier of lugs, engage against the rack bar 23 while the next tier engages beneath the next section of the releasing device and the third 85 tier beneath the third section of the releasing device, and so on. The sections 24 are successively shorter than the rack bar 23 and shorter one than the other by a distance equal to the length of one of the tiers of the 90 retaining lugs. Each section of the slide or releasing member is thus adapted to control the release of one tier of holding lugs. Through the action of means to be herein- 95 after described, the rack bar 23 first is ac- 100 tuated step by step a distance each time equal to the length of one of the lugs, so that at first the upper tier of frames is released one at a time. As soon as the first tier is released a lug 47 carried on the under-surface of rack bar 23 and extending into a slot provided in the upper surface of the next lower section, engages the lower end of that slot so that the second section is taken up 105 and the next tier of frames successively re- 110 leased. This action continues, the sections of the releasing device being successively operated, until the desired or entire number of frames have been released. When these frames are upon the right hand side of the 115 casing, they lie on top of each other in the manner shown, and as they are successively released and swung through the action of the springs 13 onto the opposite leaf, they again pile up in succession, one above the other. It will be noted from Fig. 4 that the arms 12 are so shaped as to have their outer ends disposed in a plane coincident with the plane in which the frames to which they are connected lie. In Fig. 4 only six of the 120 frames have been illustrated, but it will be understood that obviously more frames may be used if desired, or a smaller number may be used without departing from the spirit of the invention. In Fig. 6 three sections of 125 the releasing device have been illustrated and nine of the retaining lugs have been indicated, so as to readily set forth the arrangement desired. No specific limitation is set upon the number of lugs which may be 130

arranged in each tier, since if desired two or more lugs may form one tier.

- The mechanism for actuating the releasing means includes a cylinder 28 fastened in a suitable manner upon leaf 5 and within which a piston 29 is adapted to play. This piston is provided with a stem 30 which extends out through a closure 31 connected with the cylinder, and which is then bent outwardly and returned as at 32 and hingedly connected as at 33 with a detent or finger 34 adapted to engage with the teeth 35 provided on the floor of a channel formed in the outer edge of the rack bar 23. A coiled spring 36 arranged within the cylinder 28 bears at one end against the closure 31 and at its other end against piston 29, and normally retains said piston at the inner extremity of its path of movement. A stop 37 disposed upon the piston stem 30 acts as a means for limiting the outward movement of said stem, and hence the movement of the finger 34 longitudinally of the guide 22. A pneumatic bulb 38 communicates through a tube 39 with the cylinder 28 behind the piston 29, whereby when the bulb is compressed the piston will be moved outwardly. This tube 39 extends through a suitable opening provided in the end wall 9, and the length of the tube occurring on the inner side of the wall, as indicated in Fig. 1, is great enough to allow said wall to be swung into downward dotted line position shown in Fig. 4. The pneumatic bulb may be made in any suitable shape or size to be readily operated by the foot of the musician, or if preferable, by hand. The finger 34 is normally retained in engagement with the rack bar through the medium of a spring 40 interposed between the finger and the adjacent portion of the piston stem. The finger, by riding in the channel, is prevented from becoming disengaged from the teeth.
- Each time the bulb 38 is pressed, the piston 29 is forced outwardly until stop 37 strikes the closure 31, and thus the finger 34 is moved downwardly relatively to the guide 22 and carries with it the rack bar 23. The length of throw of the finger 34 is equal to the length of one of the lugs 21, so that the rack bar is thus successively moved downwardly step by step, whereby to release one of the frames each time the bulb is actuated. When all or the desired number of frames have been released, they may be manually turned to the right hand side of the casing, and the finger 34 may then be moved out of engagement with the rack bar 23 by means of a knob 42 formed on the finger, and the latter may be raised to overlie the rack bar, out of engagement with the teeth, while the rack is being moved upwardly. By moving the rack bar into its upper position, the sections 24 of the releasing device will be returned to the position indicated in Fig. 6, by
- reason of the engagement of the lugs 27 with the upper extremities of the channels in which they play. When this position of the bar has been attained, the finger 3 may again be moved to engage the teeth, and the device will be ready for operation.
- I claim:—
1. A music leaf turner comprising a pair of leaves hingedly connected, a rod carried thereby, a plurality of rectangular spring actuated music leaf receiving frames rotatably connected with the rod and normally retained in stacked position upon one of the leaves, bars adjustably mounted on each of the frames and having means for receiving a sheet of music, means for normally retaining the music leaf receiving frames in stacked position, and means for actuating the last said means whereby the frames may be successively released. 85
  2. A music leaf turner comprising a pair of hingedly connected leaves, a rod carried by one of the leaves, a plurality of spring actuated music leaf receiving frames rotatably connected with the rod and normally retained in stacked position upon one of the leaves, lugs carried by the frames and arranged in tiers one below another, said tiers being out of alignment with each other, a guide mounted upon one of the leaves adjacent the stacked frames, a slide carried by the guide and comprising a plurality of sections arranged one below another in stepped relation, each of the sections being engaged by one of the tiers of lugs, means 100 for operating one of the sections step by step, and coöperating means between the sections for successively imparting motion to them as the tiers are released. 95
  3. A music leaf turner including a pair of hingedly connected leaves, a rod carried thereby, spring actuated music leaf receiving frames rotatably connected with the rod and normally retained in stacked position upon one of the leaves, lugs carried by the 110 frames and arranged in tiers, a sectional slide engaging the tiers of lugs for restraining the frames in stacked position, a guide upon which the slide is mounted, and pneumatic means for operating the slide for 115 successively releasing the frames. 105
  4. In a music leaf turner, a plurality of spring actuated music leaf receiving frames, a sectional slide including a plurality of sections arranged in operable relation with each other, one of the sections being provided with a series of rack teeth, means carried by the frames and engaged by the slide for restraining the frames in a predetermined position, and pneumatic means for 120 operating the sectional slide, including a finger for successively engaging the rack teeth on the said one section. 125
  5. In a music leaf turner, a plurality of spring actuated music leaf receiving frames, 130

lugs carried by the frames, a sectional slide including sections arranged in operable relation with each other and normally engaging the lugs for restraining the frames in predetermined position, and means for actuating the sectional slide for successively releasing the lugs.

6. In a music leaf turner, a rod, substantially L-shaped arms rotatably mounted upon said rod, music leaf receiving frames provided with arms having squared portions adapted to engage in squared recesses provided in the first said arms, means for binding the first said arms and the music frame carried arms together, springs carried by the rod and engaging said rod supported arms, releasing means adapted to maintain the frames in stacked position against the tension of the springs, and means for operating said releasing means whereby to release the frames one at a time.

7. A music leaf turner including a rec-

tangular rigid frame, a plurality of bars formed of spring material and having over-turned ends slidably engaging opposite ends 25 of the frame, and fingers punched from the bars and extending alternately on opposite sides of said bars, the said fingers being directed toward the inner edges of the bars.

8. A music leaf turner including a plurality of rotatably supported spring actuated music leaf receiving frames normally retained in stacked position, lugs carried by the frames and arranged in tiers, a sectional slide including sections each engaging one of the tiers of lugs, means for operating one of the sections step by step, and coöperating means between the sections for successively imparting motion to them as the tiers are released.
